US0D1054463S

(12) **United States Design Patent** (10) Patent No.: **US D1,054,463 S**
(45) Date of Patent: ** Dec. 17, 2024

(54) **DRILLING TOOL**

(71) Applicant: **TMT Tapping Measuring Technology Sàrl**, Luxembourg (LU)

(72) Inventor: **Jean-Francois Stumper**, Contern (LU)

(73) Assignee: **TMT Tapping Measuring Technology Sàrl**, Luxembourg (LU)

(**) Term: **15 Years**

(21) Appl. No.: **35/518,808**

(22) Filed: **Oct. 9, 2023**

(80) **Hague Agreement Data**

Int. Filing Date: **Oct. 9, 2023**

Int. Reg. No.: **DM/232432**

Int. Reg. Date: **Oct. 9, 2023**

Int. Reg. Pub. Date: **Oct. 27, 2023**

(51) LOC (14) Cl. **15-09**

(52) U.S. Cl.

USPC **D15/139**

(58) **Field of Classification Search**

USPC D15/132, 138, 139

CPC B23B 31/113

Andrew D. Dorisio

(57) **CLAIM**

The ornamental design for a drilling tool as shown and described.

DESCRIPTION

Fig. 1.1 is a perspective view of the drilling tool showing our new design;

Fig. 1.2 is a front view thereof;

Fig. 1.3 is a top view thereof;

Fig. 1.4 is a rear view thereof;

Fig. 1.5 is a bottom view thereof;

Fig. 1.6 is an additional rear view thereof;

Fig. 1.7 is a right view thereof;

Fig. 1.8 is a left view thereof.

1 Claim, 8 Drawing Sheets
